UNITED STATES PATENT OFFICE.

FREDERICK JOHN CHAMBERS, OF LONDON, ENGLAND, ASSIGNOR TO AUTOMATIC TELEPHONE MANUFACTURING COMPANY LIMITED, OF LIVERPOOL, ENGLAND.

TRANSMITTER FOR SIGNALING BY ELECTROMAGNETIC WAVES.

1,185,479.

Specification of Letters Patent.

Patented May 30, 1916.

Application filed February 8, 1912. Serial No. 676,190.

To all whom it may concern:

Be it known that I, FREDERICK JOHN CHAMBERS, a subject of the King of Great Britain, residing in London, England, and whose post-office address is 4 Princes Square, London, England, engineer, have invented an Improved Transmitter for Signaling by Electromagnetic Waves, of which the following is a specification.

This invention relates to an improved method of producing highly damped oscillations for signaling by electromagnetic waves in what are generally known as "shock" or "impact" excitation methods. In these systems either the primary circuit receives oscillations across a spark gap, which is rapidly quenched and imparts its energy to a secondary circuit connected with the antenna, or energy is imparted to an antenna circuit which may or may not contain a spark gap across certain supply gaps, which are themselves rapidly rendered non-conductive. The first method is identified with Wien's name and the second with Lodge's.

It has been shown that the best effects will be obtained when the primary spark lasts only until the associated antenna has built up its maximum intensity. At that instant the primary spark would be completely quenched and the antenna left to oscillate free from the reaction of the primary.

The object of the present invention is an arrangement of a series multiple spark gap combined with the proper choice of the electric constants of the circuit associated with it, which will fulfil as nearly as possible the above-mentioned condition.

According to the invention a multiple spark is used in which each individual spark is formed between non-parallel surfaces closely adjacent, maintained substantially at a constant distance apart, the opposing surfaces are in relative motion, the electrodes are constructed so as to have considerable heat capacity and may be artificially cooled, the spark gaps are in series and the number of electrodes such that the voltage applied to the system may have any value. The rapid quenching of the sparks is due partly to the rotation of the electrodes, partly to the short length of each individual spark and to the heat capacity of the electrodes and also to the arrangement by which the ratio of primary capacity to primary inductance

tance is made as large as is practicable, that is the primary inductance is reduced as far as is consistent with tight coupling and the capacity limited only by the value which fails to "start" the generator when the feed circuit is closed. To completely absorb the energy of the primary circuit and to radiate this into the surrounding medium, a tight coupling and good radiating properties of the antenna are essential.

The time period of the primary circuit is made considerably greater than that of the antenna circuit or secondary circuit associated with the antenna. In this way practically undamped trains of oscillations are set up in the secondary circuit, whose time period will be controlled by its own electrical constants. Multiple spark gaps and electrodes in relative motion have previously been employed for ordinary spark and for arc systems, in which the primary and secondary circuits are in tune with each other; and parallel faced electrodes in relative motion have been proposed for "quenched spark" excitation, but the object and arrangement of such previously known systems are different from those now proposed.

In the accompanying drawings Figure 1 is a side view, Fig. 2 a plan view partly in section, and Fig. 3 an end view of a constructional form of the electrodes according to the invention.

a, a are metallic disks preferably of electrolytic copper, which rotate with the shaft *b* but are electrically insulated from it by the insulating sleeves *c*. A collar *d* adjusted by the nuts *e* on a threaded part *p* of the shaft *b* forces the disks *a* against shoulders formed on the insulating sleeve *c*. The shaft *b* revolves in ball bearings and is driven by an electric motor or in any other convenient manner.

The electrodes *f* arranged on either side of each disk *a* are provided with curved surfaces on the sides adjacent to the disks *a* and are connected in pairs by screwed pins *h* to arms *g* mounted on short lengths of the spindle *h* which is parallel to the rotating shaft *b*. The electrodes *f* can be separately adjusted by the screwed pins so as to adjust sparking distance as required. The current passes in series from the end electrode to the adjacent copper disk and thence to the next electrode and so on in series through all the air gaps. The arms *g*

carrying the electrodes *f* can be secured in any required angular position about the spindle *h* so as to allow of the removal of the electrodes and the variation of the positions of the spark gaps. By turning the arms *g* around on the spindle *h*, the copper disks *a* can also be readily removed.

Having thus described the nature of the said invention and the best means I know of carrying the same into practical effect, I claim:

1. Means for obtaining rapidly quenched sparks in the transmission of wireless signals, comprising a plurality of parallel conducting disks of large heat capacity, insulated one from the other, a second series of disks of large heat capacity mounted in pairs and arranged eccentrically to said first-named disks, each pair of said last named disks being insulated from the remaining pairs, one of the faces of each of said last-named disks being arranged adjacent to one of the faces of one of said first-named disks to form a spark gap, and means for eccentrically adjusting one series of disks with reference to the other.

2. Means for obtaining rapidly quenched sparks in the transmission of wireless signals, comprising a plurality of parallel conducting disks of large heat capacity, insulated one from the other, a second series of disks of large heat capacity mounted in pairs, and arranged eccentrically to said first-named disks, each pair of said last-named disks being insulated from the remaining pairs, one of the faces of each of said last-named disks being arranged adjacent to one of the faces of one of said first-named disks to form a spark gap, means

Copies of this patent may be obtained for five cents each, by addressing the "Commissioner of Patents, Washington, D. C."

for eccentrically adjusting one series of 40 disks with reference to the other, and means for adjusting the distance between the faces of the adjacent disks.

3. Means for obtaining rapidly quenched sparks in the transmission of wireless signals, comprising a rotatable shaft, a plurality of conducting disks of large heat capacity secured to but insulated from said shaft, a fixed shaft parallel with said first-named shaft, a plurality of conducting arms 50 adjustably mounted on said fixed shaft, each of said arms carrying a pair of conducting disks of large heat capacity, one face of each of said last-named disks being arranged adjacent to a face of one of said first-named 55 disks form a spark gap.

4. Means for obtaining rapidly quenched sparks in the transmission of wireless signals, comprising a rotatable shaft, a plurality of conducting disks of large heat 60 capacity secured to but insulated from said shaft, a fixed shaft parallel with said rotatable shaft, a plurality of conducting arms adjustably mounted on said fixed shaft, and a pair of conducting disks of large heat 65 capacity each having a convex face mounted on each of said arms, each of said convex faces being arranged adjacent to a face of one of said first-named disks to form a spark gap.

In testimony whereof I have signed my name to this specification in the presence of two subscribing witnesses.

FREDERICK JOHN CHAMBERS.
